UNITED STATES PATENT OFFICE.

JAMES DWYER, OF DETROIT, MICHIGAN.

DESIGN FOR A COOKING-STOVE.

SPECIFICATION forming part of Design No. 19,413, dated November 12, 1889.

Application filed August 10, 1889. Serial No. 820,416. Term of patent 7 years.

To all whom it may concern:

Be it known that I, JAMES DWYER, a citizen of the United States, residing at Detroit, county of Wayne, State of Michigan, have invented a certain new and useful Design for Wood Cook-Stoves; and I declare the following to be a full, clear, and exact description of the invention, such as will enable others skilled in the art to which it pertains to make and use the same, reference being had to the accompanying drawing, which forms a part of this specification.

The drawing is a perspective view of a stove illustrating my design.

15 The essential features of my design are as follows: a foot-section provided with plain feet ornamented at the top by shell-form ornamentation, and with bands between the legs, consisting of vine-work, leaves, and a central 20 shell ornament, the said vine-work embracing rosettes adjacent to the tops of the leg. This leg-section is shown at A.

B, C, and D are flanges with plain edges constituting bands, and the lower one is carried around the lower hearth where the hearth is employed, as shown. Above the plain band B is a large oven-door F, and centrally above this is a shorter oven-door G. The fuel-door H is in one upper corner, and the field E 25 beneath the reservoir is in the other upper corner. Each of these doors and this field are ornamented by a central panel having embossed vines and leaves and surrounded by raised rolls or embossed bands.

30 E' is a bracket beneath the main hearth, ornamented by a spiral scroll.

F' is a bracket-shaped formation beneath the field or section E. It is ornamented by embossed vine-work, with a molding at the 35 edge.

The end of the stove has a central panel surrounded by a raised roll f, the panel being provided with the name of the stove.

What I claim is—

1. The design for a stove, consisting of the 45 foot-section A, ornamented as shown, the bands B, C, and D, of plain finish, the oven-doors each surrounded by an embossed roll inclosing a panel of vine-work and leaves, the fuel-door and section E, each having an 50 embossed roll inclosing a panel of vine-work and leaves, and brackets E' F', substantially as shown.

2. In the design for a cooking-stove, the doors provided with a central panel ornamented by surrounding raised rolls or bands, substantially as shown. 55

3. In the design for cooking-stoves, the oven-doors thereof, consisting of a large lower oven-door and a shorter upper oven-door centrally above it, substantially as shown. 60

4. In the design for a stove, the side comprising the large lower oven-door, the shorter oven-door arranged centrally above it, the fuel-door, and the field beneath the reservoir, 65 each having a central panel ornamented with embossed scrolls and leaves and each surrounded by a raised embossed roll or band, substantially as shown.

5. In the design for a stove, the stove end 70 having a central panel ornamented at the top and sides by a raised roll or band and an embossed ornamentation, substantially as shown.

In testimony whereof I sign this specification in the presence of two witnesses.

JAMES DWYER.
